2-749
1406

AU EX
OR D 020,295

DESIGN.

—o—
G. HARGRAVE.
SKIRT.

20,295.

Patented Nov. 11, 1890

UNITED STATES PATENT OFFICE.

GEORGE HARGRAVE, OF PHILADELPHIA, PENNSYLVANIA.

DESIGN FOR A SKIRT.

SPECIFICATION forming part of Design No. 20,295, dated November 11, 1890.

Application filed July 29, 1890. Serial No. 360,332. Term of patent 3½ years.

To all whom it may concern:

Be it known that I, GEORGE HARGRAVE, of Philadelphia, in the State of Pennsylvania, have invented and produced a new and original Design for Ladies' Skirts, of which the following is a specification, reference being had to the accompanying photographic representation thereof.

The prominent features of my design consist in a series or large number of substantially straight and parallel bars running vertically throughout the upper portion of the skirt, which, for purposes of convenience, may be termed the "waist" portion, and a series of zigzag lines or bars running vertically and substantially parallel to one another from the lower ends of said straight bars throughout the lower portion of the skirt, said straight and zigzag bars being of a different color from the ground or main fabric of the skirt. In-termidate between said straight and zigzag bars are light-ribbed lines of the same color as the ground or fabric of the skirt, said ribbed lines being straight at the portions which are between the straight bars and waved or undulating at the portions which are between the zigzag bars. 25

In the accompanying representation the straight bars in the waist portion of the skirt are indicated by a and the zigzag bars in the lower portion by c. The ribbed lines are shown at b.

Having thus described my invention, I claim—

The design for a skirt, substantially as shown and above set forth.

GEORGE HARGRAVE.

Witnesses:

JABEZ GATES,
WILLIAM H. EMHARDT.